UNITED STATES PATENT OFFICE.

ARTHUR E. PEW, JR., OF BRYN MAWR, PENNSYLVANIA, ASSIGNOR TO SUN OIL COMPANY, OF PHILADELPHIA, PENNSYLVANIA, A CORPORATION OF NEW JERSEY.

PROCESS OF DISTILLING MINERAL OIL.

Application filed December 22, 1926. Serial No. 156,289.

The use of steam in stills for distilling hydrocarbon mixtures, and particularly mineral oil, for the purpose of agitation and consequent turbulence, with lowered vapor tension due to the presence of the steam, has long been known and practiced, both in stills operating at substantially atmospheric pressure and in stills operating under vacuum. There are many plants today operating at quite high vacuums which use steam as a means for agitating the oil in the stills, thus preventing accumulation of dirt on the bottom sheets and incidentally lowering the boiling point of the oils by 10 lowering the vapor tension. The turbulence obtained in a still by the use of steam materially increases the capacity of the still, since the heat transfer is much greater than when the still is run "dry".

However, it has long been thought that the use of steam necessarily results in the overhead distillate being of inferior color as compared with such oils obtained in high vacuum distillation without the use of steam. In the course of my experimental work, I distilled various oils under vacuums ranging from 28 to 29 inches. In order to lower the boiling points of the oil under this vacuum and in order to get good agitations to prevent burning and local overheating, steam was admitted beneath the surface of the oil. The steam was generated in a still under a vacuum slightly lower than the vacuum in the still. This was necessary in order to 20 generate enough pressure in the steam still to push steam through the oil in the oil still. The distillates thus obtained were of better quality than were obtained from the distillation of the same oil under a vacuum of from 3 to 4 mm. without the presence of steam. The reasons for this result I believe to be as follows:

The volume of one pound of steam at atmospheric pressure is 26.79 cubic feet. The volume of one pound of steam at 28.5 inches of vacuum is 469 cubic feet. By the process of generating steam under vacuum, the steam has fully expanded, or substantially so, when it enters the oil in the still. This makes it necessary to use less steam than would be

required in a still operating at atmospheric pressure with steam at ordinary pressure, the agitating effect of steam being largely volumetric. Steam could be admitted to the still from a line operating at any pressure, but the instant the steam leaves the nozzles and is injected into the oil in the stills when such still is operating under high vacuum, it is subject to the absolute pressure which is on the still, namely, a very high vacuum. The steam expands instantaneously according to the difference of pressure at the injector and that on the still. This rapid expansion has a tendency to cause entrainment as the steam passes upward through the oil. This entrainment would have a bad effect on the color of the distillates. However, when steam is generated under substantially the same vacuum as is applied to the oil still, the steam is already expanded at the instant it hits the oil.

As a matter of operating economy, it is quite efficient to use steam generated under vacuum, since on all vacuum plants it is necessary to have a vacuum pump or steam ejector, and the exhaust steam from such apparatus can be used through coils in the boiler for the generation of steam under vacuum. For example, the boiling point of water at 27.3 inches of vacuum is only 110° F., whereas the temperature of steam at two pounds gauge pressure is 218° F., giving a difference in temperature of 108°, which is ample for the transfer of heat from steam to water economically.

However, the reasons which have just been outlined do not fully explain the great benefit to be derived from the present process. Ordinary boiler feed water contains from 1% to 4% of air by volume. Air is 78% nitrogen by volume and approximately 21% oxygen, the balance being argon. When such water is distilled and the steam used in an oil still, the air enters the hot oil along with the steam in more than sufficient quantities to cause substantial oxidation of the distillates. Evidence of this is comparatively poor color and noticeable acidity.

The fact that air in water causes corrosion is well known in boiler practice, corrosion being the result of oxidation. The last described operation affords definite proof that 5 the oxygen in the air does act as an oxidizing agent.

Air is held in water volumetrically, and therefore, by causing the water to flow in a thin film over a plate, thereby reducing the 10 static pressure to practically zero, and by maintaining a high vacuum over the film, thereby relieving the external pressure on the surface of the water, the air will expand (if the vacuum is 2 mm.) some 380 15 times. Therefore, per cubic foot of water, there would be left in the water, after the air has expanded, only $\frac{1}{380}$ of the original air content. Water can be deaerated by other methods. For example, advantage can 20 be taken of known laws of partial pressures by bubbling exhaust steam through the water in such quantities that the resultant total pressure would be very great in proportion to the partial pressure due to the air in the 25 water. By removing air from water by any suitable method, and then converting such air-free water into steam, and injecting the steam into a body of oil being distilled under vacuum, distillates are obtained that are 30 satisfactory as to color as well as to general quality.

This last described process constitutes, broadly, my invention, although the process embodies other important features, which 35 can best be understood by an explanation of the apparatus shown in the accompanying drawing. Although the process is not dependent for its execution on any particular apparatus, that herein illustrated and 40 described has been found efficient.

The figure is a diagrammatic view of apparatus wherein my invention may be practiced.

Water is pumped through line 8, at a temperature of approximately 120° F., into an evaporator tank 10. Here the water flows at high velocities and in turn films over inclined plates 9. Tank 10 is maintained under a vacuum of (say) 28 inches. At 28 45 inches of vacuum, the boiling point of water is 100° F. and at 26.4 inches of vacuum it is 120° F. Hence, due to the vacuum in the tank being 28 inches and the temperature of the incoming water 120° F., enough water 50 boils to reduce the temperature of the water to 100° F. At this point, the pressure and temperature balance and no more water is distilled off. Air and water vapor pass upward through manifolds 7 and 6 and 55 through line 4 to brine cooler 2. Cooled brine is pumped through tubes in this cooler, thereby extracting the heat from the water vapor and air, and thus condensing the water. The air is sucked to a vacuum pump

or ejector (not shown) through line 5. The 65 condensed water is run out through line 51 to storage tank, or is mixed in with the feed through line 52, as desired.

Water substantially free of air then flows 70 from the bottom of evaporator 10 into line 11 and thence into boiler 12. Difference in elevation between vaporizer 10 and boiler 12, or a seal on line 11, compensates for the difference in pressure between boiler 12 and vaporizer 10. On the assumption that still 75 19 operates at 28.9 inches of vacuum and has 4 feet of oil in the still, this head of oil is equivalent to a pressure of about 75 mm., which is equivalent to 3 inches of mercury. Hence, in order to get the steam from boiler 80 12 into still 19 there must be a vacuum in boiler 12 of 25.9 inches or a little less, depending on line friction, say 25.5 inches. Under this vacuum, water boils at 130° F. Summarizing: vaporizer 10 is maintained at 85 28 inches of vacuum, water entering at 120° F. and leaving at 100° F.; boiler 12 is maintained at 25.5 inches of vacuum and the water is heated therein to 130° F., still 19 is maintained at 28.9 inches of vacuum and 90 contains oil having a depth of four feet.

Steam is admitted through pipe 13 to the steam coil in the boiler. This steam may be the exhaust from the vacuum pump. The 95 condensed steam is run out as water through pipe 14. A drain 15 is appended to the boiler.

Still 19 is charged through line 18 and 100 may be drained through line 17. The still may be run continuously or intermittently. Steam from boiler 12 passes through line 16 and into distributor pipes 20, whence it flows through the main body of oil in still 19.

Oil vapors and steam leave still 19 105 through pipe 21 and pass into tower 22. This tower is surrounded by an insulated air jacket 23, air being admitted through flues 24 and passing upwards through passages 23 and past damper 31 into the atmosphere. The described passage of air cools the mixture of oil vapors and steam to any desired degree. In the illustrated apparatus the vapors are cooled sufficiently to condense 110 the lubricating oil fractions, which pass out through line 25 and condenser 26 into receiving tank 27, and through line 29 to pump and storage. A vacuum is maintained 115 on this tank through lines 28 and 40 to a vacuum pump (not shown).

The uncondensed steam and lighter oils 120 pass out the top of tower 22 by means of line 32 to separator 34-35.

This separator is constructed with an air jacket 33 similar to the air jacket in tower 125 22. A mixture of oil vapors and steam passes downward through the annular chamber 34 and thence upward through the inner or central chamber 35. In traversing

these chambers the oil vapors are condensed, transferring their heat to the air in jacket 33. The condensed oil runs out through line 36, cooler 37 and line 38 to tank 41, and 5 thence through line 42 to storage. A vacuum is maintained by means of lines 39 and 40 to the last mentioned vacuum pump.

The steam, still uncondensed, passes out 10 the top of chamber 35 through line 45 to a barometric injection condenser 46. Here water is injected through line 47 into condenser 46, which condenses the steam, the condensate and the injected water passing down stand pipe 48 to a barometric seal 55, 15 which has an overflow through line 53, and a drain 54. Water vapors and non-condensable still gases pass into an ejector or a wet or dry vacuum pump 49. If this is an ejector, steam is admitted through line 56 and 20 exhausted through line 50.

There are substantial advantages in adapting the invention to other processes of distilling oil, such as those disclosed in the applications filed by Pew and Thomas March 5, 25 1925, Serial No. 13,040, and by me May 29, 1926, Serial No. 112,485; but the described application of the invention to a simple and well known type of oil still (19) discloses the invention in a simple form. It will be 30 understood, however, that the process is applicable to any known method of vacuum distillation.

Having now fully described my invention, what I claim and desire to protect by Letters Patent is:

1. The process of vaporizing oil which comprises removing air from water, generating steam from such water and mixing such steam with the oil.

40 2. The process of vaporizing oil which comprises removing air from water, generating steam from such water under a partial vacuum, mixing such steam with the oil, and maintaining a higher vacuum on the oil during its vaporization.

45 3. The process of vaporizing oil which comprises flowing water in shallow streams over extended surfaces while subjecting it to a high vacuum and thereby deaerating the water, generating steam from such water under a substantial vacuum, mixing said steam with the oil, and maintaining the oil under a higher vacuum than that under which the steam is generated.

50 5. The process of distilling oil which comprises flowing water in a shallow stream over extended surfaces while subjecting it to a high vacuum and thereby removing most of the air from the water, heating the aerated water to convert it into steam substantially devoid of air, injecting said steam into the oil while maintaining the oil under vacuum, and condensing the oil vapors, thereby enabling the production of an oil 55 distillate substantially free from the decom-

position products produced by high temperature and substantially free from the oxidation products produced by the contact of the oil with oxygen.

5. The process of distilling oil which comprises removing air from water, generating steam from such water, mixing such steam with the oil, and by heat exchange with a current of air condensing oil vapors and separating them from uncondensed steam. 75

6. The process of distilling oil which comprises removing air from water, generating steam from such water, mixing such steam with the oil, condensing the heavier oil vapors and separating them and lighter oil 80 vapors from uncondensed steam by heat exchange of the oil vapors and steam with a current of air, and passing uncondensed steam and lighter oil vapors into heat exchange with a current of air and thereby condensing such lighter oil vapors and separating them from uncondensed steam. 85

7. The process of distilling oil which comprises removing air from water, generating steam from such water, mixing such 90 steam with the oil, condensing oil vapors and separating them from uncondensed steam by heat exchange of the oil vapors and steam with a current of air, and condensing the steam from which the condensed oil has 95 separated.

8. The process of distilling oil to produce distillates of high quality and good color notwithstanding the injection of steam into the oil, which comprises substantially avoiding oxidation of the distillates by mixing 100 with the oil steam from which a greatly predominant proportion of its content of air has been removed.

9. The process of distilling oil which comprises maintaining the oil under a low sub-atmospheric pressure and mixing with the oil steam under a sub-atmospheric pressure sufficiently higher than the pressure on the oil to enable the steam to be forced into the 105 oil and sufficiently low to minimize the volumetric expansion of the steam when admitted to the oil and the resultant entrainment as the steam travels through the oil.

10. The process of distilling oil of high 115 quality and good color at relatively low temperatures, which comprises maintaining the oil under a low sub-atmospheric pressure and mixing therewith steam from which a predominating proportion of air has been 120 removed and forcing the deaerated steam into the oil under a sub-atmospheric pressure above that to which the oil is subjected but sufficiently low to minimize the effect of its expansion and the resultant entrainment as 125 the steam travels through the oil.

11. The process of vaporizing oil which comprises removing air from water, generating steam from such water, maintaining on the oil a low sub-atmospheric absolute 130

pressure lower than the absolute pressure under which the steam was generated, and mixing the steam, as it is generated, with the oil.

- 5 12. The process of vaporizing oil which comprises removing air from water by flowing the water over an extended surface while subjecting it to a low sub-atmospheric pressure, generating steam from said water
10 under a higher sub-atmospheric pressure,

mixing such steam with the oil, and maintaining on the oil a sub-atmospheric absolute pressure lower than the absolute pressure under which the steam was generated.

In testimony of which invention, I have 15 hereunto set my hand, at Philadelphia, Pennsylvania, on this 15th day of December, 1926.

ARTHUR E. PEW, Jr.
